UNITED STATES PATENT OFFICE.

JACOB H. SHEAR, OF ALBANY, NEW YORK.

IMPROVEMENT IN COOKING-STOVES.

Specification forming part of Letters Patent No. 38,423, dated May 5, 1863.

To all whom it may concern:

Be it known that I, JACOB H. SHEAR, of the city of Albany, State of New York, have invented a new and useful Improvement in the Construction of Cooking-Stoves; and I declare the following specification, with the drawings forming part thereof, to be a full and complete description of my invention.

The drawings represent a cooking-stove of the usual form, with the right-hand side plate and portions of the flue-plates removed to show the internal construction of the stove as designed by me.

A is the furnace or fire chamber; X, the oven; B, the upper flue opening into the space betwixt the back plates of the oven and stove, which space is divided by partitions into three vertical flues, C D E, which three flues are continued betwixt the bottom plates of the oven and stove to near the front of the stove at G. (This is the usual arrangement of three flue stoves.) A damper is fitted at the junction of the upper flue, B, and the center flue, D, by which the entrance to flue B can be closed and the egress of smoke and gas through the exit-flue or nozzle N cut off. In that case the smoke and gases are compelled to pass down the side and bottom flues, C and E, to G, and then return through the center flue, D, up out at the nozzle N. There is a second upper flue, H, placed between the top of the oven X and the bottom plate of flue B, extending from the fire-box the entire length and breadth of the top of the oven. Communication between it and flue D is cut off, but is open to C and E its entire cross-section, excepting that part closed to D. There is also another flue, M, arranged between the front of plate I of the upper section of the oven and the back plate, K, of the fire-box, and extending the entire width of the stove. Openings a a in the place marked by dots are made in that part of the side plates which cover the ends of this flue to admit the external air to the flue M. Openings b b are made in the plate I to permit the heated air to pass from flue M into the oven X. Other openings e e are also made in the top plate of the oven near the front plate, I, to permit the air from the oven to pass out into flue H.

From that flue it passes down the side flues, C and E, mingling with the current of smoke and gases from flue B and passing under the oven on its way to the exit-pipe N. The object of this arrangement is to equalize the heat as much as possible in all parts of the oven. When the bottom plate of the upper flue forms the top of the oven and the back plate of the fire box the front end of the oven, the heat becomes accumulated in the upper part of the oven, and so much of it is absorbed by the plates mentioned that the residuum which passes down under the oven in the "diving-flues" (so called) has little heat left to warm its bottom plate. Now, the effect of the interposed flues H and M is to moderate the heat applied to the upper and end plates of the oven, while at the same time, by the current of air introduced between them, all the heat from the back plates of the fire-box and the bottom of the upper flue are saved and carried along, yielding a liberal proportion of caloric to the oven-plates, but carrying also with the smoke and gases a large proportion to the back and bottom flues, giving to the base of the oven a heat very far beyond what any present arrangement of flues can yield. It also promotes materially the draft of the stove when the heat and gases are sent down through the entire flues, a point in which all diving-flue stoves fail greatly, making their success depend entirely upon the superior draft of the chimney they use. This arrangement also secures a full ventilation of the oven, carrying off all deleterious gases and disagreeable odors from the cooking viands.

What I claim as my invention, and desire to secure by Letters Patent, is—

The combination of the flue M and its openings a a b b, flue H and its openings e e, and its openings into flues C and E, with the back and bottom flutes, C D E, in the manner and for the purposes set forth in the above specification.

J. H. SHEAR.
